UNITED STATES PATENT OFFICE.

HARRY B. HILLS, OF RIVERTON, NEW JERSEY.

BOAT.

1,243,938.

Specification of Letters Patent. Patented Oct. 23, 1917.

Application filed May 5, 1917. Serial No. 166,518.

To all whom it may concern:

Be it known that I, HARRY B. HILLS, a citizen of the United States of America, and resident of Riverton, county of Burlington, State of New Jersey, have invented a certain new and useful Improvement in Boats, of which the following is a true and exact description, reference being had to the accompanying drawings, which form a part thereof.

My present invention relates to boats and particularly to the construction of metal boats used as ships' boats or lifeboats, and the general object of my invention is to provide a boat suitable for the purpose mentioned which shall be simple and inexpensive of construction, inherently strong and of high stability.

A distinguishing characteristic of my invention is the formation of a boat hull of desirable shape out of a comparatively small number of metal plates, the surfaces of which while curved are formed altogether, or for the most part, of straight line elements.

In a preferred practical mode of carrying out my invention I form each plate in sections which merge into one another, and each of which forms a portion of the wall of a hollow cone, though some of the plate sections may be flat, cylindrical or ellipsoidal without interfering with the attainment of the general object of my invention.

The invention possesses the distinct practical advantage that plates of the character described may be given their special shape by subjecting flat blanks to simple bending operations, the curvature at any point of a plate being transverse to the straight line element of the surface of the plate passing through that point. In the ordinary practice of my invention the blanks are bent about forms into the desired shape. The formation of the plates by simple bending operations avoids the necessity for special and more expensive shaping operations, and in practice makes possible the construction of a boat from a smaller number of plates and with a corresponding reduction in the amount of riveting required.

The various features of novelty which characterize my invention are pointed out with particularity in the claims annexed to and forming a part of this specification. For a better understanding of the invention, however, and the advantages possessed by it, reference should be had to the accompanying

drawings and descriptive matter, in which I have illustrated and described a preferred embodiment of my invention.

Of the drawings:

Figure 1 is an elevation of a ship's boat constructed in accordance with the present invention;

Fig. 2 is a plan view of the boat shown in Fig. 1;

Fig. 3 is a transverse section taken on the line 3—3 of Fig. 1;

Fig. 4 is a diagrammatic front end view or body plan;

Fig. 5 is a diagrammatic view with the boat shown in side elevation;

Fig. 6 is a diagrammatic view with the boat shown in front elevation; and

Fig. 7 is a diagrammatic view with a portion of the boat shown in plan.

In the desirable embodiment of my invention illustrated in the drawings, the skin of the boat is made up of two side plates A, and two bottom plates B. The two bottom plates B are provided at their adjacent edges with parallel flange portions B', which, with the intervening keel C, are riveted together by rivets D. The plates B are also formed with flange portions B² which rise slightly above the bilge knuckle, and are fastened by rivets D to the overlapping lower edges of the plates A. The plates A are provided at the opposite ends of the boat with flange portions A' riveted to the stem and the stern post of the boat. In the boat, as shown, the opposite ends of the hull body are alike. The boat is shown as stiffened by attaching two chafing pieces F to each plate A, one chafing piece being at the top of the plate and the other at the level of the thwarts G. As shown, the boat is provided with longitudinally running side seats H mounted on the thwarts G. Underneath the seats are arranged the air tanks I, and bottom boards K run along the upper sides of the bottom plates B.

As diagrammatically illustrated in Figs. 5, 6 and 7, each plate A may be regarded as formed in five sections, namely a middle section made up of conical surface elements O, two end sections each made up of conical elements L, and two intermediate sections made up of conical elements M. One of the conical elements M at each end of the boat coincides with one of the conical elements L, and another conical element M at each end of the boat corresponds with

one of the conical elements O. The apices L' and M' of the cones, of which the lines L and M respectively are elements, appear in Figs. 5 and 6. For convenience of illustration the elements L and M are shown in Figs. 5 and 6 as of half the relative lengths actually given them in a preferred boat construction devised and built by me. It is understood, however, that my invention is not limited to any special proportioning of such dimension. The cone of which the lines O are elements has its apex so far removed from the boat that with the scale of the drawings of Figs. 5 and 6 the different lines 15 O appear to be parallel. In Fig. 7 the dotted lines O², M² and L² represent intersections of the cones of which the lines O, M and L are elements respectively, by a plane parallel to the surface of the water.

20 The bottom plates B are each formed, as shown, with a central conical surface portion of which the elements are represented by the lines Q, and conical end sections. The lines P shown represent the elements of 25 the conical end surface of the left hand end of the rear bottom plate B of the boat, as it appears in Fig. 5. P' represents the apex of the cone of which the lines P shown in Figs. 5 and 6 are elements. The apex of the cone 30 of which the lines Q are elements is so far from the boat that the different elements Q shown in Fig. 5 appear practically as parallel lines.

35 In practice, the plates A and B are given their general shapes by bending them about forms, and without subjecting them to any

forging or stretching operation. At the same time the curvature given the plates is of a character and extent sufficient to give the plate great strength and rigidity to resist forces tending to deform the hull of the boat. After the plates are bent to shape they are subjected to a forging or flanging operation to properly form the flange portions B' and B² on the bottom plates B and 40 the flange portions A' at the ends of the side plates A.

The boat shown and formed in the manner described is obviously relatively simple and inexpensive to construct, and well 45 adapted to be turned out in great rapidity when built in numbers. The shape of hull, and the fact that this shape lends itself to a relatively low placing of the seats H makes possible a boat of desirably high stability. 50

Having now described my invention what I claim as new and desire to secure by Letters Patent is:

1. A boat having its hull formed wholly or in part of plates each comprising sections 60 forming parts of hollow cones, the axes of which are transverse to the longitudinal axis of the boat.

2. A boat having its hull formed of curved metal plates each so curved that 65 through any point in the surface thereof a straight line element passes which is inclined to other straight line surface elements of the plate but does not intersect therewith within the margin of the plate.

HARRY B. HILLS.
